CLAIM

The ornamental design for a red light therapy gua sha, as shown and described.

DESCRIPTION

FIG. 1 illustrates a front perspective view of a red light therapy gua sha;

FIG. 2 illustrates a front view of the red light therapy gua sha thereof;

FIG. 3 illustrates a back view of the red light therapy gua sha thereof;

FIG. 4 illustrates a left side view of the red light therapy gua sha thereof;

FIG. 5 illustrates a right side view of the red light therapy gua sha thereof;

FIG. 6 illustrates a top view of the red light therapy gua sha thereof;

FIG. 7 illustrates a bottom view of the red light therapy gua sha thereof;

FIG. 8 illustrates an exploded front perspective view of the red light therapy gua sha thereof;

FIG. 9 illustrates an exploded bottom perspective view of the red light therapy gua sha thereof;

FIG. 10 illustrates an exploded left side view of the red light therapy gua sha thereof;

FIG. 11 illustrates an exploded right side view of the red light therapy gua sha thereof;

FIG. 12 illustrates an exploded top view of the red light therapy gua sha thereof; and,

FIG. 13 illustrates an exploded bottom view of the red light therapy gua sha thereof.

The broken lines in the drawings depict portions of the red light therapy gua sha that form no part of the claimed design.
